(57) **CLAIM**

The ornamental design for a vehicle front lower grille, as shown and described.

DESCRIPTION

FIG. 1 is a front elevational view of a vehicle front lower grille, showing our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a top, front and left side perspective view thereof; and,

FIG. 7 is a bottom, front and left side perspective view thereof.

The broken lines show a claim boundary. Neither the broken lines themselves nor the half-tone portion of the grille bordered by the dashed line form any part of the claimed design.
